UNITED STATES PATENT OFFICE

GEORG HEDLER, OF ARZBERG, GERMANY

DESIGN FOR A PLATE OR SIMILAR ARTICLE

Application filed April 8, 1931. Serial No. 39,400. Term of patent 7 years.

To all whom it may concern:

Be it known that I, GEORG HEDLER, a citizen of the Republic of Germany, residing in the city of Arzberg, county of Oberfranken, State of Bavaria, in the Republic of Germany, have invented a new and original Design for a Plate or Similar Article, of which the following is a specification, reference being had to the accompanying drawing, forming a part thereof in which the figure is a plan view showing the new design.

The ornamentation shown is continued throughout the border of the plate.

I claim:

The ornamental design for a plate or similar article as shown and described.

GEORG HEDLER.
